A. J. Stover,

Cook Stove.

Patented Jan. 7, 1835.

Jan. 4, 1835

Abraham D'Unger of Greene County New York
Letters Patent

It is desired and to give these letters patent and making part of the same as follows a description in the words of the said Abraham D'Unger himself of his improvement in Stoves for cooking with anthracite coal called the "Hudson Cooking Stove":

It all is when stoves are built as now, the want of sufficient space and the limited extent of the horizontal surface of the fire in stoves, cooking with anthracite coal, hitherto however have made it difficult if not impossible to expose more than one or two feet of the fire at once, to the degree of heat necessary to carry on culinary operations to advantage - and whence also it has been found difficult in such stoves, to increase or diminish the fire suddenly for different purposes, therefore -

Be it known that Abraham D'Unger of the Town of Coxsackie Co. of Greene and State of New York have invented a new and useful improvement in Stoves, for cooking with anthracite Coal called the Hudson Cooking Stove, by which it is intended to obviate the above difficulties, and of which the following is a true and exact Specification: The circular form (the most usual) being the best adapted to the arrangement that is to be made of the boiler and other apparatus for cooking is one that will now be described. This Stove consists of a hollow cast iron cylinder of from twelve to fifteen inches high, placed vertically one circular hearth of about double the diameter both having a common center. The grate is suspended within this cylinder about midway between the base and top and it may be adjusted for rest or motion, and the fuel above the grate may be lined with brick, stone, or other nonconductor of heat the ash-draught may be above or below the hearth and should entirely close the entrance for air at the base of the cylinder. On the top of this cylinder is placed another hollow and constrictive cylinder, of double the diameter of the lower one, or some larger if required. This may be about six inches in height and the lower plate of the upper cylinder has an opening on its outer edge equal in extent to the top of the lower cylinder and

at the margin of this opening, the two cylinders are formed together and united into one common chamber. The upper plate of the upper cylinder, or the top of the stove has several openings for boiling and heating, or other cooking utensils, the openings, for these being in such order and arrangement that all of them to the number of three or more, stand partly over and are directly exposed to the fire, and may consequently be kept boiling at the same time, thus avoiding the necessity of removing one after another successively to the fire, or of giving a rotary motion to the plate in which they are contained to attain the necessary degree of heat. For managing the heat under either of the boilers, a further provision is made by means of a flue within the periphery of the upper cylinder to extend from the opening for the pipe both ways, so as nearly to meet in front and encircle the stove. Lateral outlets are made into this flue opposite to each boiler, which outlets, or openings are provided with dampers, to shut or open them as occasion requires. The opening with the collar for the attachment of pipe may be on the outside of the periphery of the upper cylinder and there should always be a damper in the pipe to regulate the fire. The baking, Roasting and other similar operations, are performed in separate boilers, and roasters of suitable construction placed at proper distance around the lower cylinder or furnace.

I claim as my invention and improvement the drum or upper cylinder with the openings, for boilers, in the top, so placed in relation to the lower cylinder or furnace that all the boilers to the number of three or more shall be partly over and directly exposed to the fire and so as to be kept at the required temperature at the same time and also the circular flue with lateral openings, and dampers, for regulating the draft under either of the boilers, whom required whether said flue be constructed within or on the outside of the upper cylinder, and the general arrangement and combination of the respective parts, so as to constitute a cooking stove operating upon the principle or in the manner described.
